DESIGN FOR A FOLDING, PORTABLE BAR

Howard J. Barrett, Philadelphia, Pa.

Application January 18, 1947, Serial No. 136,246

Term of patent 14 years

(Cl. D33—19)

To all whom it may concern:

Be it known that I, Howard J. Barrett, a citizen of the United States of America and a resident of Philadelphia, county of Philadelphia, and State of Pennsylvania, have invented a new, original, and ornamental Design for a Folding, Portable Bar, of which the following is a specification, reference being had to the accompanying drawing, forming part thereof, in which:

Fig. 1 is a front elevation of a folding, portable bar showing my new design as it appears in its opened position.

Fig. 2 is a rear perspective view of the same.

Fig. 3 is a rear elevational view of the folding, portable bar as it appears in its closed position.

The characteristic features of the design are shown in solid lines.

I claim:

The ornamental design for a folding, portable bar, as shown and described.

HOWARD J. BARRETT.
